CLAIM

The ornamental design for a connection game, as shown and described.

DESCRIPTION

FIG. 1 is a perspective view of a connection game showing my new design;

FIG. 2 is a front elevational view thereof;

FIG. 3 is a left side view thereof;

FIG. 4 is a top plan view thereof; and,

FIG. 5 is a bottom plan view thereof.

The broken lines in the drawing depict portions of the connection game that form no part of the claimed design.
